ELECTRICAL PLUG CONNECTOR

Kenneth Perkins, Scotch Plains, N. J., assignor
to The Singer Manufacturing Company, Elizabeth, N. J., a corporation of New Jersey

Original application September 30, 1939, Serial
No. 297,268. Divided and this application April
12, 1940, Serial No. 329,262

4 Claims. (Cl. 173—332)

This invention relates to electrical plug-connectors adapted, more particularly, for use with motor-driven family sewing machines.

An object of the invention is to provide a plug-connector having improved casing and contact elements which are readily manufactured and assembled.

Another object of the invention is to provide a plug-connector the live metallic parts of which are at no time so exposed that they can be touched by anyone.

A further object of the invention is the incorporation in the connector of an exposed ground contact which is well separated and thoroughly insulated from the unexposed live contacts.

Still further, the invention has for an object to provide a plug-connector the casing of which is provided with special cord inlets adapting it particularly to the requirements of electric sewing machine outfits.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a perspective view of the motor bracket of an electric sewing machine carrying a connector the plug-member of which embodies the invention. Fig. 2 is a perspective view of the connector socket-member shown in Fig. 1 which is adapted to receive a plug-member embodying the invention. Fig. 3 is a perspective view of the plug-member, complete. Figs. 4 and 5 are perspective views of the two halves of the plug-member. Fig. 6 is a central transverse section through the plug-member. Fig. 7 is a perspective view of a special rubber plug for use with the plug-connector when wired for use with a treadle or knee operated rheostat. Fig. 8 is a diagram of connections for the plug-connector when used with a knee or treadle operated controller built into a sewing machine cabinet, and Fig. 9 is a diagram of connections for the connector when used with a foot-operated controller to be placed on the floor where desired.

This application is a division of my copending application Serial No. 297,268, filed Sept. 30, 1939.

1 represents the cast iron motor-supporting bracket of a sewing machine, such as repre-

sented in U. S. Patent No. 1,488,234, dated Mar. 25, 1924. As shown in said patent this bracket has a slotted foot portion 2, which is bolted to the bracket-arm standard of a sewing machine, 5 and an inclined end-portion 3 which carries the sewing machine driving motor. The bracket 1 is also formed with a seat 4 to which is secured by the screw 5 a socket-member 6 suitable to receive the present plug-connector. The socket-member 6 may comprise a casing of molded insulation material, preferably "Bakelite," having a plug-receiving cavity 7 from the bottom end wall 8 of which project the flat connector-blades 9 standing in edge-to-edge spaced relation. 10 There may be fastened under the head of the screw 5 a ground contact blade 10 which is in metallic connection with the iron bracket 1 and hence with the frame of the sewing machine to which the bracket 1 is bolted. This blade 10, 15 when used, is preferably set substantially flush with the top side wall of the cavity 7.

The plug-member in its preferred form comprises a hollow casing 11, having a penetrant portion 12 formed in its penetrant end with three 20 apertures 13 to receive connector-blades, such as shown at 9. The plug-member is also formed at two opposite base edges with the roughened finger-grip flanges 14. There may also be an external groove 15 in which may be disposed the 25 reversely bent end of the spring ground-contact 16 the shank 17 of which is held by the headed-over end of the metal insert 18, in which the binding screw 19 for a ground-conductor 20 is threaded.

30 The plug-casing 11 is made of two molded separable sections 21 and 22 of "Bakelite" held together by screws 23 and snap-rings 24 which latter embrace the oppositely extending conductor-receiving coaxial tubular extensions 25, 26 35 formed at the base of the penetrant portion 12 of the plug casing. These extensions 25, 26 are formed internally with the strain-relieving ribs 27 which grip the conductor-cord insulation when the parts are assembled. The longitudinal axes 40 of the coaxial tubular projections 25, 26 lie substantially in the parting plane of the separable sections 21, 22.

The plug-section 22 is preferably formed internally with three square posts 28 which are 45 spaced apart and from the side walls of the section 22. Into the grooved top ends of these posts are riveted, by metal inserts, the shanks of the return-bent spring-contacts 29 which all face in the same direction and are within the openings 13 so as to be engaged by the contact blades

9 when the plug 11 is inserted in the socket-cavity 7. Binding screws 30 for the lead-in wires are threaded into the metal inserts by which the contacts 29 are riveted in position. One of the side walls 31, Fig. 6, is formed with contact-spring rest grooves 32.

The plug-section 21 is formed with the internal tubular portions 33 which surround the fastening screws 23. It is also formed with a cavity 34 for the lead-in wires.

The plug-member 11 has at the base of the reduced penetrant portion 12, a vertical planar stop-wall 12' which contacts the edge of the receiving end of the socket-member 6 and definitely limits the insertion distance of the plug-member 11 therein. It will also be noted that the outer surfaces at one side of the plug-member are stepped; the vertical stop-wall 12' constituting a step riser and the adjoining portions of the penetrant and thicker ends of the casing constituting the step treads. The ground contact 16 is similarly stepped and is thus made long enough to possess the requisite resiliency.

It will be further noted that the shanks of the contacts 29, Fig. 6, bridge a gap between the rest grooves 32 and posts 28. These gaps permit the blade shanks to flex downwardly when the prongs 9, Fig. 2, engage and depress the return bent portions of the contacts 29. This provision relieves the strain to which the bends at the ends of the contacts 29 are subjected.

When the motor-speed controller 35 is built into a sewing machine cabinet it is more conveniently wired to the socket-member 6, together with the light L and motor M, as shown in Fig. 8. In this case three lead-in wires, including two current-supply wires and one ground wire 20 are led through the opening of the tubular projection 26 of the plug-member 11 and connected, as shown, to the two outside contacts 29 and to the ground-contact 16. The center contact 29 is not used. The tubular lead-in projection 25 is not used and is filled by the double-headed rubber plug 36.

When the motor-speed controller 35 is to be placed on the floor or moved about, as desired, it is more convenient to wire it to the plug-member 11, as shown in Fig. 9. Here, the connections of the current-supply wires and ground wire 20 are the same as in Fig. 8, but the controller leads 37, which run through the tubular extension 25, vacated by the rubber plug 36, are connected to the center and right hand contacts 29.

When the halves of the plug-member 11 are fastened together, the live contacts 29 therewithin are completely covered and cannot be touched by anyone.

The current supply cord runs, without kinking, from a wall plug at the rear of the machine into the rearwardly directed cord inlet extension 26 while the cord of the controller, which is normally located on the floor in front of the machine runs, without kinking, into the forwardly directed cord inlet extension 25.

The device is structurally well adapted for con- 65

venient use with the various known types of electrically lighted and motor-driven sewing machine outfits.

Having thus set forth the nature of the invention what I claim herein is:

5 1. A connector member comprising a casing of insulation material formed in two half-sections and having a cavity therewithin, and a parting plane, one of said half-sections being formed with internal posts projecting into said cavity in a direction transverse to said parting plane, said posts being formed at their free ends with shallow flat-bottomed grooves defining seats parallel to said parting plane, a set of contact blade 10 springs having thin shank ends secured flatwise to said seats and having return bends at their other ends, said post-containing casing section having steady-rest grooves in a wall portion thereof spaced from said posts, said steady-rest 15 grooves receiving the bends of said contact springs, the other casing section having contact-prong-admission grooves in register with said steady-rest grooves.

2. A connector member comprising a casing of insulation material formed in two half-sections and having a cavity therewithin and a parting plane, one of said sections being formed at one side with a stepped outer wall having two tread portions and an intermediate riser portion, all of 20 which portions are formed with a stepped ground-contact-blade receiving groove having two treads and an intermediate riser portion, and a stepped ground-contact spring-blade having two treads and an intermediate riser portion disposed in said groove and secured at one end to one of said treads.

3. A connector comprising a hollow casing having a penetrant end-portion and a thicker opposite end-portion, a stepped ground-contact spring 40 blade having two treads and an intermediate riser portion secured by one of said treads to the thicker end portion of said casing, externally of the latter, the other tread extending onto and toward the free end of said penetrant portion externally of the latter, and live contact elements mounted within the penetrant portion of said hollow casing.

4. A connector member comprising a casing of insulation material formed in two separable sections and having a cavity therewithin, one of said sections being formed with an internal post projecting into and spaced from the walls of said cavity, said post being formed at its free end with a seat transverse to the direction of length of said post, a contact blade spring having a thin shank end secured to said seat and having a return bend at its other end, said post-containing casing section having a steady-rest groove in a wall portion thereof spaced from said post, said steady-rest groove receiving the bend of said contact spring, said casing having a contact-prong-admission groove in register with said steady-rest groove.

KENNETH PERKINS.
